(57) **CLAIM**

The ornamental design for a bird feeder, as shown and described.

DESCRIPTION

FIG. 1 is a perspective view of a bird feeder showing my new ornamental design;

FIG. 2 is a front view of the bird feeder shown in FIG. 1;

FIG. 3 is top view of the bird feeder shown in FIG. 1;

FIG. 4 is a view of the bird feeder taken from the left side of FIG. 2;

FIG. 5 is a view of the bird feeder taken from the right side of FIG. 2; and

FIG. 6 is a bottom view of the bird feeder shown in FIG. 2; and,

FIG. 7 is a rear view of the bird feeder of the present invention.

The portions shown in broken line are for illustrative purposes only and form no part of the claimed design.
